J. G. NOLEN

REFRACTOR

Filed Dec. 1, 1923

Inventor:
James G. Nolen,

By his attorney

Harold D. Penney

UNITED STATES PATENT OFFICE.

JAMES G. NOLEN, OF NEW YORK, N. Y.

REFRACTOR.

Application filed December 1, 1923. Serial No. 677,971.

To all whom it may concern:

Be it known that I, JAMES G. NOLEN, citizen of the United States, and resident of New York, in the county of New York and 5 State of New York, have invented certain new and useful Improvements in Refractors, of which the following is a specification.

This invention pertains to light refracting means essentially designed for head-lights, 10 or lamps such as used on motor vehicles and similar places.

The object of the invention is to provide an improved arrangement whereby the rays from the lamps are projected forward in a 15 narrow cone at the center or in the axis of the light, while all of the surrounding light rays are broken up or diffused.

A further object of the invention is to provide a light controlling member of this character that can be readily applied to existing forms of lamps, especially where a parabolic reflector is employed.

In the accompanying drawing showing 20 one embodiment of my invention, Figure 1 is a vertical section of the device.

Fig. 2 is a fragmentary section taken on the line A—B, indicated in Fig. 1.

The invention as set forth comprises essentially a shell of substantially conical form, with the walls practically concavo-convex as shown. This shell at its larger open end is bent outwardly to form an annular flange, by which the member is conveniently mounted on the front of a lamp, 35 especially one having a parabolic form.

As set forth, the lamp comprises an outer shell 3 of somewhat conical form, that carries a lamp 4, such as a small incandescent lamp; in the shell is mounted a parabolic reflector 5, in the center or axis of which lies the end of a filament 6 of the lamp. By 40 this means the rays from the lamp would be projecting forward in parallel lines, if not intercepted.

The refractor is shown in the form of a shell 7 of somewhat conical form, but slightly curved similar to the reflector. At 45 the inner end portion of the shell 7, a lens 8 is formed in the shell, that is shown as convex on both its faces. The front portion of the shell 7 is provided with an outwardly extending annular flange 9. This is adapted to be mounted in the extended flange portion 10 of the lamp shell or frame 5, by any 50 suitable means, such as ring washers 11 and

12 that may be held by a deflected edge 13 of the shell.

It will be observed that the lens 8 is in the axis of the reflector 4, which will result in the rays directly from the lamp filament being projected forward in the form of a narrow or constricted cone.

The shell wall opposite the reflector and beyond the lens 8 will receive the rays from the parabolic reflector 5, and will refract them and cause their diffusion. To increase this refractive effect, I form this wall with irregular surfaces. These may be different on the inner and outer wall; as shown the inner wall of the shell 7 is formed with annular ridges 14, being substantially corrugated. The outer wall is shown as having thereon radially extended corrugations 15 that extend transversely to the ridges on the inner side, the lens 8 and ridges 14 and corrugations 15 as shown being formed integral with the shell 7. The effect of these ridges will be to cause very strong diffusion of the light rays from the reflector 5 and this will practically eliminate the glare from the lamp, the center cone of rays can be projected on to a small object a considerable distance ahead, but will not cause the blinding effect that would result from the parabolic reflector 5 if this diffusing member 85 were not employed.

What I claim is:

1. The combination with a substantially parabolic reflector having a source of light on the line of its axis at the rear of the reflector, of a substantially parabolic concavo-convex refractor supported in the reflector and having its line of axis coincident with the line of axis of the reflector and its apex near the source of light, a lens at the apex of the refractor for cooperating with the source of light, means for diffusing light arranged on the interior of the refractor circumferentially around the interior and extending forwardly from the lens, and means for diffusing light arranged on the exterior of the refractor and radiating from the lens and extending forwardly therefrom.

2. The combination with a substantially parabolic reflector having a source of light on the line of its axis at the rear of the reflector, of a substantially conical concavo-convex refractor supported in the reflector and having its line of axis coincident with

- the line of axis of the reflector and its apex near the source of light, a lens at the apex of the refractor for cooperating with the source of light, annular ridges on the interior of the refractor and extending in series forwardly from said lens, and a series of corrugations on the exterior of the refractor and radiating from the lens and extending forwardly therefrom.
- 10 3. The combination with a substantially parabolic reflector having a source of light on the line of its axis at the rear of the of the reflector, of a substantially conical concavo-convex refractor supported in the reflector and having its line of axis coin-

cident with the line of axis of the reflector and its apex near the source of light, a double convex lens at the apex of the refractor for cooperating with the source of light, annular ridges on the interior of the refractor and extending in series forwardly from said lens, and a series of corrugations on the exterior of the refractor and radiating from the lens and extending forwardly therefrom.

25

Signed at New York in the county of New York and State of New York this 23rd day of November A. D. 1923.

JAMES G. NOLEN.
